MOP SHAKING DEVICE

Jules J. Brell, New York, N. Y., assignor, by direct
and mesne assignments, to O-Cedar Corp'n,
Chicago, Ill., a corporation of Illinois

Application September 22, 1936, Serial No. 101,915

4 Claims. (Cl. 15—147)

This invention relates to an improvement in dust mops or similar articles of the character shown in my United States Patents Nos. 1,993,336 and 1,996,056, and particularly to a means by 5 which the mop may be vigorously shaken or vibrated to cause the accumulated dust and dirt to be dislodged and if desired, directed into a receptacle or on to a paper.

The object of the invention is to provide a 10 mechanism of simplified construction and of few parts whereby a rapid, vigorous vibratory movement may be imparted to the mop head causing it to effectively shake the dust and dirt from the mop strands.

15 A further object of the invention is to provide a mechanism of the character described having all of its operating parts fully enclosed and thereby having no projecting parts or elements likely to come in contact with furniture and do damage 20 to the same during the mopping or shaking operation.

A further object of the invention is to provide a fully enclosed shaking mechanism whereby the operating parts may be easily lubricated and 25 protected and which by reason of this and their sturdy construction will provide a long life of usefulness to the device.

In the accompanying drawing wherein several 30 embodiments of the invention are shown, Fig. 1 is a side elevation of a mop with the lower portion thereof in section to show the shaking mechanism; Fig. 2 is a sectional view on the line 2—2 of Fig. 1, looking in the direction of the arrows; Fig. 3 is a sectional view on the line 3—3 of Fig. 1, 35 looking in the direction of the arrows; Fig. 4 is a perspective view of the two co-operating halves of the mop head frame; Fig. 5 is a sectional view through the mop and one of the halves of the mop head frame; Fig. 6 is a side view, partly in 40 section, of a modified mop shaking structure; Fig. 7 is a sectional view of the structure shown in Fig. 6, said sectional view being taken at right angles to Fig. 6; Fig. 8 is a side elevation with parts in section of a modified structure; Fig. 9 is 45 a side elevation, partly in section, of another modified structure; and Fig. 10 is a sectional view through the structure of Fig. 9 at right angles thereto.

50 Referring to the structure disclosed in Figs. 1 to 5 inclusive, the mop stick or handle is shown at 11 and has its lower end securely fastened by bolts, screws or rivets 13 in a boss 12 forming a part of a housing 14. As will be seen in Fig. 3, the housing consists of two similar halves suitably secured together. Rotatably mounted within the housing is a segmental gear 15 which is 55 secured on the shaft 16 mounted in bearings 17 formed on the two halves of the housing 14. Said shaft 16 protrudes through the housing 14 and its ends project outside of the housing as clearly

shown in Fig. 3. These projecting ends of the shaft 16 are formed with transverse holes which receive the vertically disposed ends 18 of the mop frame section 19 (see Fig. 4). Each of said mop frame sections is preferably made of a 5 single bent section of substantially heavy wire or rod and comprises a pair of vertically spaced parallel legs 20, each of which has one of its ends bent or inturned toward the other leg 20, as indicated at 18. At their opposite ends the members 20 are connected by the integral vertical struts 21. The vertically bent ends 18 fit into the holes in the shaft 16 and may be held therein either by the resiliency of the frame 19 or may be welded or otherwise secured to the shaft 16. 15 When the two halves 19 of the mop frame are in position as shown in Fig. 3, they are spaced apart at the front end of the mop as indicated at 22 in Fig. 3 so that the mop may be easily slid in position through this opening. When in 20 position, the mop forms a substantially triangular arrangement, as clearly shown in Fig. 3.

In the drawing, a double-faced mop is shown, 25 consisting of two tufted sections 23 held together by the tape or binding 24 which forms a pocket 25 into which the frames 19 fit as clearly shown in Fig. 5. A single-sided mop of conventional form may also be used.

The segmental gear 15 meshes with and is actuated by a similar, but slightly larger, segmental gear 26 mounted upon shaft 27 rotatably mounted in the walls of the casing 14. Segmental gear 26 meshes with and is operated by a rack 28 formed at the end of actuating rod or bar 29 which is vertically reciprocal in a longitudinally 30 extending groove 30 formed in the stick 11. A guide roller 31 mounted in casing 14 rotates against the outer surface of the rack 28 thereby holding it in constant mesh with the segmental gear 26. Through the arrangement disclosed it 35 will be obvious that when the actuating rod or bar 29 is reciprocated up and down in the groove 30, it will oscillate the gear 26 causing the same to oscillate gear 15, thereby vibrating or rapidly oscillating the mop frame sections 19 to shake 40 the mop and dislodge the dust and dirt therefrom. The means for so reciprocating the bar 29 comprises a sleeve 31 surrounding the handle 11 and movable thereon and secured to the upper 45 end of the bar 29. The upper end of the bar 29 is formed with a laterally bent end 32 entering into the sleeve 31, which is preferably made of wood, and thereby attaches the sleeve to the bar 29. Bumpers or stops 33 of rubber or other material are secured in properly spaced relationship on the stick 11, to restrict or limit the sliding movement of the sleeve 32 during its reciprocation. 50

55 It will be noted that the entire operating mechanism is enclosed so that possibility of 60

damage to furniture and household equipment is prevented. That is to say, the gears and other mechanism, including the lower rack portion of the operating bar 29 are all completely enclosed and confined within the housing 14. The operating bar 29 is also movable within its groove 30 so that the finished mop presents a smooth and symmetrical appearance. It will be noted that two segmental gears 15 and 26 are employed rather than one because it is necessary to keep the lower end of the housing elevated or above the floor during the mopping operation and this could not be done if the mop frame were, for example, secured to shaft 27 rather than to shaft 16.

In Fig. 6 a somewhat similar construction is shown except that an additional gear is used in order to secure a more symmetrical housing for the gears. There, the housing is shown at 30 and it contains two superimposed meshed gears 31 and 32. The lower gear is mounted upon shaft 33 which has its ends projecting from the casing as clearly shown in Fig. 7, these ends receiving the mop head frames 19 in the manner described in respect to the structure of Figs. 1 to 5 inclusive. The upper gear 31 rotates upon the shaft 34 and said gear 31 is attached to a pinion 35 engaged by the rack 28 formed on the end of actuating bar 29, as described with respect to the structure of Fig. 1. It will be obvious that as bar 29 is reciprocated up and down, it will through the gearing described, oscillate shaft 33 to thereby vigorously shake the mop mounted thereon.

In Fig. 8 is shown a casing 40 constructed similarly to that described in Fig. 1 and secured to the mop stick 11 in the same way. Casing 40 contains two sprockets 41 and 42, spaced apart and connected by a chain 43. The lower sprocket 42 has a shaft 44 projecting outside of the casing and secured to the mop frames 19 in the manner described in connection with shafts 16 and 33. The lower end of the actuating bar 29 is inwardly bent or off-set at 45 and said end is pivotally attached at 46 to one of the links of the chain. In this construction, it will be apparent that as the actuating bar 29 is reciprocated up and down by movements of the sleeve 31, it will move the chain 43 back and forth over sprockets 41 and 42 thereby oscillating shaft 44 and vibrating the attached mop frame and mop in a manner similar to that previously described with respect to the structures of Figs. 1 and 6.

In Fig. 9 is shown a casing 40 similar to that described with reference to Fig. 8. Mounted in the casing 40 are spaced pulleys 50 and 51, the lowermost pulley 51 being mounted upon shaft 52 which is attached to the mop frames 19 in the manner previously described. The upper pulley 50 is mounted either on a rotatable shaft 53 or mounted to rotate on a fixed shaft. Pulleys 50 and 51 are connected by a drive cord or cable 54. The lower pulley 51 is double-grooved as clearly shown in Fig. 10, to permit sufficient oscillatory movement of shaft 52. The ends of cable or cord 54 engaging the grooves in the pulley 51 are attached in said grooves. The reciprocating bar 29 has its lower end operating within the casing 40 and attached at 55 to the cord 54. With the structure of Figs. 9 and 10, it will be obvious that as the bar 29 is reciprocated up and down in the groove 30, it will move the operating cord or cable 54 over the pulleys 50 and 51 to thereby oscillate the pulleys and cause shaft 52 to rapidly shake the mop to dislodge the dust and dirt accumulated therein.

In the various embodiments of the invention herein described, all of the operating parts are enclosed and protected. This is particularly true of the actuating bar 29 which has its lower end confined and movable within the casing so that this lower end cannot through vigorous operation of the bar engage mop strands or other parts of the mop to damage the mop and is also prevented from striking against or in any way damaging furniture or parts of the home.

What I claim is:

1. A mop-shaking device comprising, a mop stick, a housing attached to one end of the same, a shaft rotatably mounted in said housing and having its ends projecting outside of the housing for connection to mop frames, an actuating member movable on the stick, means in the housing for communicating the movements of the actuating member to the shaft to thereby oscillate said shaft, the shaft being provided with holes at its ends, mop frames having superimposed vertically spaced leg portions formed with ends directed toward one another, said ends entering the holes in the shaft and attaching the frames to said shaft.

2. A mop-shaking device comprising, a mop stick, a housing secured at one end of the same, an oscillating shaft rotatably mounted in the housing and having ends projecting externally of the housing for connection to a mop frame, a substantially rigid mop frame composed of two separate halves, one end of each of said halves being attached to one of the shaft ends, and the other end of each of said halves remaining open to permit the placing of a swab thereon without removal of said frame from said shaft, an actuating member reciprocable longitudinally of the stick, a rack portion on said actuating member, and gear means within the housing and engaging said rack portion for oscillating the shaft when the actuating member is reciprocated.

3. A mop-shaking device comprising, a mop stick, a housing secured at one end of the same, a shaft extending transversely through said housing and having its ends projecting out of the sides of the same, a mop frame composed of two separate sections, one end of each of which is attached to a shaft end, a gear mounted on said shaft, a second gear rotatably mounted within the housing and meshing with the first-mentioned gear, an actuating member reciprocable on the stick, a rack moved by reciprocating movement of said member, said rack meshing with the second gear, and stop means adapted to prevent movement of said rack beyond the extreme portion of said first-mentioned gear.

4. A map-shaking device comprising a mop stick, a housing secured at one end of the same, an oscillating shaft mounted in said housing and extending transversely therethrough with exposed ends, mop frames mounted on said shaft ends, said mop frames being spaced at one point to permit the placing of a swab thereon without removal of said frame from said shaft, a gear mounted on said shaft, a second gear rotatably mounted within said housing above said first-mentioned gear and meshing therewith, an actuating member reciprocable on the stick, a rack meshing with said second-mentioned gear and moved by the reciprocating movement of said member, and stop means adapted to prevent the movement of said rack below the lower portion of said first-mentioned gear.
